C. H. ALLEN.
LIGHT REGULATOR.
APPLICATION FILED AUG. 11, 1916.

1,262,427.

Patented Apr. 9, 1918.

Inventor
Charles H. Allen.
By his Attorney

W. J. Pinwell.

UNITED STATES PATENT OFFICE.

CHARLES H. ALLEN, OF OAKLAND, NEW JERSEY.

LIGHT-REGULATOR.

1,262,427.

Specification of Letters Patent.

Patented Apr. 9, 1918.

Application filed August 11, 1916. Serial No. 114,407.

To all whom it may concern:

Be it known that I, CHARLES H. ALLEN, a citizen of the United States, and a resident of Oakland, in the county of Bergen and 5 State of New Jersey, have invented a certain new and useful Improvement in Light-Regulators, of which the following is a full, clear, and exact specification.

This invention relates more particularly to 10 a class of devices adapted to be used in conjunction with vehicle lamps.

My invention has for its object primarily to provide a device adapted to be applied especially to the lamps providing the headlights of automobiles and like vehicles so that the rays of light will be deflected in front of the vehicle at an angle toward the highway on which it is traveling in order to avoid accidents to persons traveling on the 15 highway toward the vehicle by being confused from the glare of the lamps of the approaching vehicle as is incident to the present methods in use wherein the light is reflected direct ahead of the vehicle on a similar longitudinal plane to the lamp. This is accomplished mainly by providing a reflecting element adapted to be applied to the casing of a vehicle lamp with a reflector therein so that the reflecting element will be disposed in front of the lamp as well as being disposed relatively to the reflector so that the rays of light will be reflected to the reflector of the casing and then deflected on an angle toward the highway on which the vehicle 20 may be traveling.

Other objects of the invention are to provide an expansible and contractible member to allow the reflecting element to be applied to the casings of vehicle lamps of various 25 sizes; to provide one or a number of retaining elements for removably holding the expansible and contractible member in the casing; and to provide a light regulator of a very simple and durable construction.

45 A practical embodiment of the invention is represented in the accompanying drawing forming a part of this specification in which similar characters of reference indicate corresponding parts in all the views, the said 50 invention being more fully described hereinafter, and then pointed out in the claim at the end of the description.

In the drawing, Figure 1 is a side view of one form of light regulator embodying my invention showing the manner of its use in conjunction with a vehicle lamp, the lamp being shown in section taken therethrough 55

Fig. 2 is an enlarged front elevation of the device.

Fig. 3 is a section taken on the line 60 III—III of Fig. 2.

Fig. 4 is a view looking down on the device shown in Fig. 2.

Fig. 5 is a side view of a different form of light regulator as applied to a vehicle lamp 65 part of which is shown in section.

Fig. 6 is an enlarged front elevation of the device illustrated in Fig. 5.

Fig. 7 is a section, partly in detail, taken on the line VII—VII of Fig. 6.

Fig. 8 is a view looking down on the device shown in Fig. 6, and

Fig. 9 is a sectional view taken on the line IX—IX of Fig. 5.

The device, or light regulator has a reflecting element 10 adapted to be applied 75 interiorly of the casing, as 11, of a form of lamp usually employed on an automobile and like vehicle for serving to provide a headlight, such lamps being ordinarily made 80 with a casing of substantially a parabolic, or cup-shape having a mirrored, or reflecting inner surface, as 12, while its open front is closed by a glass door 13 mounted in a frame, as 14, which may be releasably locked 85 to the casing in any suitable manner, for example in Figs. 5 and 9 is indicated the frame as being hinged, as 15, to the casing while a commonly used type of catch, as 16, is employed for releasably fastening the 90 door to the casing, this catch being composed of a plate 17 with one end hinged to the door frame, and the plate has an apertured second end bent angularly so as to be swung upon the side of the lamp casing. Projecting from the casing of the lamp, and in the path of movement of the apertured plate, is a threaded bolt 18 over which the apertured plate is removably guided when the catch is fastened, the bolt 95 having a thumb screw 19 on its threaded end for holding the plate thereon, or in some forms of the lamp casing adjacent the door may be a number of spaced orifices,

as 20 Fig. 1, while the light distributed through the front door may be supplied by an electrically lighted lamp 21, or the lamp may be otherwise lighted.

5 The reflecting element 10 shown in Figs. 1, 2, 3, 4 is preferably in the form of a circular body, or plate of metal having a mirrored, or reflecting surface, as 23, and this reflecting element, or plate is made of a 10 diameter to adapt it to removably fit closely in the open front of the casing 11 of the lamp adjacent to the back of its door. In the upper half of the plate 10 is an opening 24 of approximately a semi-elliptic 15 shape for the rays of light from the lamp in the casing to pass therethrough, and the lower part, or reflector proper of this plate is disposed angularly with respect to the upper part of the plate so that when the 20 plate is fitted in the lamp its upper apertured portion will be on a vertical line, while the lower portion will be disposed on an incline interiorly of the casing of the lamp, as illustrated. On the lower edge of the 25 inclined part of the mirrored plate 10 is an apron, or flange 25 which extends toward the door of the lamp, and this apron is of a width as well as being formed so that its free edge will be on vertical alinement with 30 the apertured upper portion of the plate for this apron to abut against the frame of the door of the lamp casing.

In order to removably hold the reflecting element, or mirrored plate 10 in the casing 35 of the lamp, one or a number of retaining elements, or catches, as 26, are provided. All of the retaining elements 26 are preferably in the forms of pliable metal strips, or fingers, and these retaining elements extend 40 laterally from spaced parts of the edge of the apertured upper half of the mirrored plate 10. When the device is applied to the lamp after the glass door with the frame 14 is removed from the casing of the lamp, 45 the pliable retaining elements, or fingers 26 are bent so that each may be removably disposed through one of the orifices 20 of the casing of the lamp, and the plate 10 is then arranged, as above described, so that the 50 inclined portion of the plate will obscure the lower part of the lamp. The free end portions of the retaining elements are then bent over on the exterior of the casing of the lamp, and the device will then be removably held to the lamp, the retaining 55 elements 26 being of sufficient lengths to overlap the contiguous part of the lamp casing. When the lamp in the casing 11 is lighted, following the reapplication of the 60 glass door 13 to the casing, the rays of light will be reflected by the mirrored surface 23 of the inclined portion of the plate 10 to the lower part of the reflecting surface 12 of the casing 11, then to the upper part of the 65 reflecting surface of the casing, and the rays

will be deflected on an angle through the opening 24 of the plate to the highway on which the vehicle may be traveling.

When the device is of a form illustrated in Figs. 5, 6, 7, 8, 9, the reflecting element 27 70

may be in the form of a metallic plate having a mirrored, or reflecting surface, as 28, and as the casings of these vehicle lamps are generally circular in shape the reflecting element, or plate 10 is preferably semi-circular 75

as well as being of a size so as to be disposed within the casing of the lamp for causing the rays of light of the lamp to be deflected through about one-half of the glass door 13.

This semi-circular mirrored plate is employed in the front part interiorly of the casing of the lamp so as to be disposed also on an incline, and serving to removably hold the plate 28 against accidental movement, or displacement, an extensible and contractible 80

holding member, as 29, is provided. The holding member 29 is preferably in the form of a ring, or band of spring metal part of which is separated, as at 30, and on one end of these separated parts is a fixed tube 31 of 85

a length so that its free end extends some distance beyond this end of the band for being disposed toward the second end thereof to removably receive the second end of the band for allowing the ends of the band to be 90

adjustably connected. The ends of the reflecting element, or mirrored plate 27 at its straight edge are soldered, or otherwise secured to diametrically opposite parts centrally of the holding member, or band 29 so 95

as to be disposed angularly, or on an acute angle with relation to the band, in order that its curved parts will be spaced from the band, or holding member 29. The device 100

when applied to a vehicle lamp of the form 105 shown in Fig. 5 the holding member 29 is sprung interiorly of the casing of the lamp so as to be adjacent to the frame of its glass door as well as to arrange the reflecting element, or plate 27 on an incline transversely 110

in the upper part of the casing of the lamp. This upper part of the interior of the casing will then be obscured, and the reflecting element will receive the rays of light from 115

the lamp so as to be reflected to the reflecting surface of the casing of the lamp. The light rays will then be deflected through the lower part of the glass door of the casing on an angle toward the highway in front of the vehicle.

To removably fasten the holding member, or band 29 to the casing of the lamp one, or more retaining elements, as 32 and 33, are provided. Both of the retaining elements 32 and 33 are preferably in the forms of metal 125

strips extending from opposite parts of the holding member, or band in directions toward the reflecting element, or plate 27, and in each of these retaining strips is a notch, or recess, as 34, to allow one strip to be 130

guided over the hinge 15 between the door 13 and the casing, while the other strip is disposed over the bolt 18 of the catch 16 of the casing of the lamp. In this manner a 5 simple and efficient light regulator is provided for the lamps of automobiles and other vehicles whereby the rays of light will be deflected in front of the vehicle at an angle to avoid accidents to persons traveling on the 10 highway toward the vehicle by being confused from the glare of the lamps of the approaching vehicle.

In the foregoing description, I have embodied the preferred form of my invention, 15 but I do not wish to be understood as limiting myself thereto, as I am aware that modifications may be made therein without departing from the principle, or sacrificing any of the advantages of this invention, 20 therefore I reserve to myself the right to make such changes as fairly fall within the scope thereof.

Having thus described my invention, I claim as new and desire to secure by Letters Patent:—

In a light regulator, a contractible and expandible holding member adapted to be applied in the casing of a vehicle lamp with a reflector therein, a reflecting element on the holding member, disposed on an incline 30 in the casing and with relation to the reflector whereby the rays of light of the lamp will be reflected to the reflector of the casing and then deflected on an angle toward the highway on which the vehicle is traveling, and a retaining element for detachably fastening the holding member to the casing. 35

This specification signed and witnessed this tenth day of August, A. D. 1916.

CHARLES H. ALLEN.
